UNITED STATES PATENT OFFICE.

ROBERT FULTON COLLINS, OF MANCHESTER, OHIO.

CHURN.

SPECIFICATION forming part of Letters Patent No. 429,506, dated June 3, 1890.

Application filed August 16, 1889. Serial No. 320,921. (No model.)

To all whom it may concern:

Be it known that I, ROBERT FULTON COLLINS, a citizen of the United States, and a resident of Manchester, in the county of Adams 5 and State of Ohio, have invented certain new and useful Improvements in Churns; and I do hereby declare that the following is a full, clear, and exact description of the invention, which will enable others skilled in the 10 art to which it appertains to make and use the same.

This invention relates to churning, and has for its object certain improvements in a mechanism for imparting a reciprocating revolving 15 motion to the dasher. I attain this object by the mechanism illustrated in the accompanying drawings, in which—

Figure 1 is a perspective view of the mechanism. Fig. 2 is a central longitudinal section view of the same. Figs. 3 and 4 are detail views; and Fig. 5 is a detail view of the bottom piece of the rectangular frame, showing the slot therein and the hinged piece pivoted within said slot.

Like letters of reference denote corresponding parts in all the figures.

The letter A designates a frame having a circular base, mounted for convenience on casters and two upright standards. In the 30 top of this frame is constructed a rectangular box, the bottom piece B of which is furnished with a slot D and hinged piece E. This slot D, as will be seen more clearly by reference to Fig. 5 of the drawings, extends inwardly 35 from the front of the bottom piece or partition, and then laterally, the end thereof which receives the dasher-staff being rounded, so as to conform to the shape of said staff, the entire slot being approximately L-shaped. The 40 top piece C of said box is also provided with a slot F, over which closes a perforated and socketed button G. The dasher-shaft H is provided with a groove I, bearing in the rounded end of the slot D, and has its upper 45 end reduced at J, registering with the bearing formed by the slot F and socket g of the button G. The hinged piece E is mounted upon a transverse shaft in the lateral extension of the slot D, and has its free end fitting 50 in the groove I of the dasher-staff, said free end being rounded to conform to the shape

of the staff. A removable stem L, bearing a fan M, is adapted to be inserted through an aperture in the button G into a socket K, cut in the end of the dasher-shaft. When this 55 stem is thus applied, the fan will be kept in motion by the revolution of the dasher-shaft, and flies and other insects kept from congregating about the churn.

The dasher is rotated by means of a cord 60 N, which is passed several times around the shaft between the grooves I and J, and has its ends fastened one to each of the levers O. These levers are fulcrumed on a rod P, inserted through the upwardly-projecting and 65 trifurcated end Q of one of the upright standards. The top piece C is also trifurcated at the end joining this standard, and suitable ways for the operation of the levers O are thus provided. Each lever has a pair of branching 70 sockets o p, in either of which suitable lever-handles may be inserted.

In operating the mechanism the dasher is placed in a churn and the churn set on the circular base. At the same time the grooves 75 I and J of the dasher-shaft are placed in their respective bearings and the hinged piece E pressed down into engagement with the groove I, as previously explained. Of course, when it is desired to remove the staff, all that is 80 necessary to be done is simply to force the hinged piece E upward out of engagement with the groove I, when the staff is free to be taken out of its bearings. If it is desired to use the fan, the stem L is inserted 85 through the aperture g into the socket K. The cord N is adjusted as heretofore shown and the levers O alternately operated in opposite directions, by means of which the dasher is revolved about twice around and 90 back. If the lever-handles be inserted in the inner pair of sockets, they will describe an arc of a circle from points between a horizontal and a vertical line, and if inserted in the outer pair of sockets the motions will 95 be right and left, or in an arc of a circle described between two oblique lines, so that they can be conveniently operated by a person either sitting or standing. The box may be closed when operating by means of the hinged 100 door R, which is fastened by a turn-button.

As before stated, the free end of the hinged

piece E is rounded or recessed to conform to the shape of the staff, and this recess is of such depth or size as to allow the end of the piece to pass by the shoulder above the part 5 I, as seen in Fig. 2, when said piece is raised or depressed.

As to the form of the dasher proper and of the churn-barrel with which it is to be used, I make no claim, and they therefore need not 10 be particularly described.

Having thus described my invention, I claim and desire to secure by Letters Patent of the United States—

1. The herein-described churn, consisting 15 of the frame having the upwardly-extended trifurcated side piece, the levers having the branching sockets and fulcrumed in the trifurcated side piece, the cords connected to said levers and the dasher-shaft, the dasher having 20 its shaft formed with a groove and its upper end reduced, the partition having an opening to receive the groove of the shaft, the fan fitting in said shaft, and the button in which the fan-shaft turns, all as shown and described.
2. In a churn, the combination of uprights, 25 one of said uprights being provided with a trifurcated upper end, a top piece provided with a trifurcated end registering with the trifurcated end of the standard, and also pro- 30 vided with the central aperture, a transverse

partition provided with an opening, a dasher-staff provided with an annular groove and having its upper end reduced, levers journaled upon a shaft in the trifurcated end of the standard and provided with vertically and obliquely projecting socketed extensions 35 adapted to interchangeably receive the ends of operating-rods, and cords connecting the lower ends of the levers with the dasher-staff, substantially as set forth.

3. In a churn, the combination, with uprights, of a top piece provided with a central aperture or opening, a hinged button closing over said opening, and provided with a socketed under surface, in combination with a 45 dasher-staff provided with a reduced and socketed upper end fitting within the socketed under surface of the turn-button, a stem passing through an aperture in said turn-button and seated within the socketed upper end of 50 the dasher-staff, said stem carrying a fan, and mechanism for imparting rotary motion to the dasher-staff, substantially as set forth.

In testimony that I claim the foregoing as my own I have hereunto affixed my signature 55 in presence of two witnesses.

ROBERT FULTON COLLINS.
